UNITED STATES PATENT OFFICE

WILHELM B. BRONANDER, OF MONTCLAIR, NEW JERSEY

FIRE EXTINGUISHER AND SUPPORT THEREFOR

Application filed October 10, 1927. Serial No. 225,060.

This invention relates to fire extinguishers and supports therefor.

The invention relates more particularly to the type of extinguisher having a fire extinguishing liquid sealed therein such, for instance, as carbon tetrachloride.

The invention has for its salient object to provide an extinguisher and support therefor so constructed and arranged that the extinguisher is easily accessible and can be readily and quickly utilized to extinguish a fire.

Another object of the invention is to provide an extinguisher so constructed and arranged that the extinguishing fluid will be automatically released in case of fire.

Another object of the invention is to provide a frangible extinguisher and support so constructed and arranged that the extinguisher will be protected from accidental breakage but can be easily and quickly broken to release the fire extinguishing fluid therein in case of fire.

Another object of the invention is to provide an extinguisher support that is simple, practical and inexpensive in construction and so constructed and arranged that the extinguisher can be easily inserted therein and removed therefrom.

Further objects of the invention will appear from the following specification taken in connection with the drawing, which forms a part of this application, and in which

Fig. 1 is a longitudinal sectional elevation of an extinguisher and support constructed in accordance with the invention;

Fig. 2 is a front elevation of a supporting bracket;

Fig. 3 is a rear elevation of the extinguisher and casing or shield;

Fig. 4 is a transverse sectional elevation taken substantially on line 4—4 of Fig. 1; and

Fig. 5 is an enlarged sectional elevation of the lower end of the extinguisher and casing showing a heat controlled releasing device for the breaking hammer.

The invention briefly described consists of a container, preferably formed of

frangible material, and containing a fire extinguishing fluid such as carbon tetrachloride, and means for supporting the container in such a way that it can be easily and quickly pulled away from its support and broken to release the fire extinguishing fluid. The frangible container is preferably substantially enclosed within a shield or casing so constructed that it can be opened up and a new container can be placed there-in after one container has been used. The casing has a hammer having a portion extending therethrough and a blow on the hammer will cause the frangible container to break, thus liberating the fire extinguishing fluid contained thereby. The hammer may, if desired, be spring actuated and be held under tension by the spring and in spaced relation to the container by a fusible member.

The casing or shield is held on a bracket or supporting member by means of resilient elements carried by the bracket or support and adapted to engage the casing. The resilient means coact with the casing in such a way that the casing can be easily removed from the bracket or support.

Further details of the invention will appear from the following description.

In the particular form of the invention illustrated the extinguisher is supported on a bracket consisting of an elongated plate 10 having its lower end 11 extending laterally to a position beneath a hammer hereinafter described. The upper end of the plate is folded back to form a lip 12.

If desired, the bracket can be supported by the loop formed at the junction of the lip 12 and the main body portion of the bracket 10. For instance, the lip may be placed over the bottom edge of a pocket in the door of an automobile. In order, however, to facilitate the attachment of the bracket to a vertical wall, counter-sunk openings 14 and 15 are formed in the body portion of the bracket and in the lip 12. An opening 16 is also formed in the bracket in alinement with the countersunk opening 14 to permit the passage of a screw through the opening 14.

The fire extinguisher illustrated comprises an elongated tubular container 20 formed of frangible material such as glass and having a depression 21 at the lower end thereof. The glass or material at the depression 21 is preferably thinner than the remaining portion of the wall to make it more frangible.

In order to protect the frangible container from accidental breakage the container is housed in and substantially covered by a casing comprising a central portion 25 and end portions 26 and 27. The central portion 25 consists of a band or sleeve having outturned flanges 30 and 31 tapered with respect to each other. The band has a plurality of lips 32 at the lower end which secure to the band the bottom dome shaped portion 27 of the casing, these lips being so located that the two free edges of the band can be bent outwardly to a sufficient extent to permit the frangible container to be withdrawn from the casing.

The band is also formed with similar lips 35 at the upper end thereof for securing thereto the upper portion 26 of the casing 23 which partially surrounds the container and extends around substantially one-half or the front half of the upper end thereof. After a container has been placed within the casing the casing is secured thereto by a clamping plate 36 having flanges 37 and 38 formed on a taper and adapted to extend around the flanges 30 and 31 of the central portion 25 of the casing.

The casing and container is secured to the bracket by means of resilient legs 40 and 41 of a U-shaped spring 42. The spring is secured to the front face of the bracket 10 by means of flanges 42 and 43 and lugs 45 and 46 formed on the flanges and extending into engagement with the spring. The upper ends of the legs 40 and 41 can slide beneath the lugs 46 to permit the legs which are bowed inwardly to be forced outwardly. In order to mount the casing and container on the bracket the casing is positioned as shown in Fig. 4 with the legs 40 and 41 engaging between the outer surface of the band or central portion 25 of the casing and the flanges 37 and 38 of the clamping plate 36. This can be accomplished by forcing one of the legs laterally and snapping the other leg into the position shown in Fig. 4 or by moving the container downwardly so that the tapered clamping plate will be positioned with its flanges behind the spring legs 40 and 41.

In order to facilitate breaking the frangible container a hammer having a head 48 and a shank 49 is slidably mounted in a bushing 50 carried by the bottom portion 27 of the container. In the form of the invention shown in Figs. 1 to 3 inclusive the hammer is normally pressed by a spring 52 against the depressed portion 21 of the lower end of the container. The portion 11 of the bracket 60 extends beneath the lower end of the hammer

shank 49 and prevents accidental engagement therewith.

In order to use the device shown in Fig. 2 the container is removed from the bracket by sliding it upwardly or merely by grasping it firmly and pulling it away from the bracket and then the shank 49 of the hammer is engaged against any suitable object and forced inwardly, breaking the lower end of the frangible container. The bottom 27 of the casing has a plurality of perforations or openings 55 to permit the fire extinguishing fluid to pass therethrough.

In the form of the invention shown in Fig. 5 the hammer is normally held in retracted position spaced from the depressed portion 21 of the container by means of a pin 56 which extends through the hammer shank 49 and beneath the lower end of the bushing 50. The pin 56 is preferably formed of fusible metal so that in case of fire the pin will melt, thereby permitting the spring 52 to force the hammer upwardly into engagement with the container, causing the container to be broken and the fire extinguishing fluid to be released. The pin 56 may, if desired, have a cord 57 secured thereto and extending in a position in which it will be accessible so that the pin can be manually withdrawn, thus releasing the hammer.

As above stated, in order to use the extinguisher it is merely necessary to grasp the casing and remove it from the bracket, whereupon the hammer can be forced inwardly to break the container and the fluid can be sprinkled or poured on the fire. Also, as stated, with the device shown in Fig. 5, in case of fire the pin 46 will melt, thus automatically releasing the fire extinguishing fluid.

After a container has been broken and the fluid has been emptied a new container can be easily and readily inserted in the casing in the manner hereinabove described.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. In combination, a bracket, an elongated container, a metallic sheath surrounding the container, means securing the sheath to the container, and interengaging means on the securing means and bracket and including resilient members for securing said means, sheath and container to the bracket.

2. In combination, a fire extinguishing container, a bracket, and means including resilient means having gripping portions dis-

- posed in a single plane securing the container to the bracket.
3. In combination, a fire extinguishing container, a bracket, and means including resilient means including a pair of inwardly bowed spring elements, having gripping portions disposed in a single plane for securing the container to the bracket.
4. In combination, a fire extinguishing container, a casing including a band encircling the container, a clamp securing the casing around the container, a bracket, and resilient means for securing the clamp, band and container to the bracket.
- 15 5. In combination, a fire extinguishing container, a casing encircling and secured to the container, a clamp securing the casing around the container, a bracket, and resilient means for releasably securing the clamp, casing and container to the bracket.
- 20 6. In combination, a fire extinguishing container, a casing including a band encircling the container, a clamp securing the band around the container, a bracket, and resilient means engaging the clamp for releasably securing the clamp, band and container to the bracket.
- 25 7. In combination, a frangible container, a casing surrounding said container, means for supporting said casing and container, a hammer carried by the casing and adapted to break the container, and a spring for forcing said hammer against the container, said casing having perforations adjacent the hammer for permitting the escape of liquid therefrom.
- 40 8. In combination, a frangible container, a casing surrounding said container, means for supporting said casing and container, a hammer carried by the casing and adapted to break the container, a spring for forcing said hammer against the container, and releasable means for retaining the spring under stress and the hammer in spaced relation to the container, said casing having perforations therein to release liquid therefrom when the container is broken.
- 45 9. In combination, a frangible container, a casing surrounding said container, means for supporting said casing and container, a hammer carried by the casing and adapted to break the container, a spring for forcing said hammer against the container, and fusible means for retaining the spring under stress and the hammer in spaced relation to the container, said casing having perforations therein to release liquid therefrom when the container is broken.
- 50 10. In combination, a frangible container, a casing surrounding said container, means including a bracket for releasably supporting said casing and container, a hammer carried by the casing and adapted to break the container, and means carried by the bracket for shielding said hammer against accidental actuation.
- 55 11. In combination, a frangible container, a casing surrounding said container, means for supporting said casing and container, a hammer carried by the casing and adapted to break the container, means for actuating the hammer in a direction toward the container, said casing having a perforated bottom adjacent the hammer through which the fire extinguishing fluid can pass when released and releasable means for holding the hammer against actuation by said actuating means.
- 60 12. In combination, a casing, a frangible container rigidly mounted therein, a hammer carried by the casing and adapted to engage and break the frangible container, means for actuating the hammer in a direction toward the container, said casing having openings therein to permit the escape of the fire extinguishing liquid released by the breaking of the container and releasable means for holding the hammer against actuation by said actuating means.
- 65 13. In combination a bracket, a casing having oppositely extending portions, a fire extinguishing container in the casing and compression springs carried by the bracket and engaging said portions of the casing so as to rigidly but releasably hold the casing on the bracket.
- 70 14. In combination a bracket having a substantially flat portion, a casing having oppositely extending portions, a fire extinguishing container in the casing and compression springs carried by the flat portion of the bracket and engaging said portions of the casing so as to rigidly but releasably hold the casing on the bracket.
- 75 15. In combination, a bracket having a vertical portion and a laterally extending portion at one end of the vertical portion, a casing, a frangible fire extinguishing container in said casing, springs carried by the vertical portion of the bracket and engaging and releasably holding the casing on the bracket, a hammer carried by the casing and adapted to engage and break the container, said laterally extending portion being located in alignment with the hammer and constituting a shield therefor when the casing is supported on the bracket.
- 80 16. In combination, a fire extinguisher support, including a cap, means for supporting a frangible fire extinguisher container on said cap, a hammer slidably mounted in said cap, a spring for actuating the hammer, and heat controlled means for holding the hammer against actuation, said cap having an opening therein to permit the escape of fire extinguishing liquid therethrough.
- 85 17. In combination, a fire extinguisher support, including a cap, means for supporting a frangible fire extinguisher container

- on said cap, a hammer slidably mounted in said cap, a spring for actuating the hammer, heat controlled means for holding the hammer against actuation, said cap having an opening therein to permit the escape of fire extinguishing liquid therethrough, and a frangible container supported above said cap and having an indented lower end disposed above said hammer.
18. In combination, a frangible container, a casing supporting said container, means for supporting said casing and container, a hammer carried by the casing and adapted to break the container, and a spring for forcing said hammer against the container, said casing having perforations adjacent the hammer for permitting the escape of liquid therefrom.
19. In combination, a frangible container, a casing supporting said container, means for supporting said casing and container, a hammer carried by the casing and adapted to break the container, and a spring for forcing said hammer against the container, said casing having perforations adjacent the hammer for permitting the escape of liquid therefrom, said container having an indented lower end disposed above said hammer.
20. In combination, a fire extinguisher support comprising an inverted cap, a hammer slidably mounted therein, a spring for actuating said hammer, heat controlled means for holding the hammer against actuation, a frangible container, and means embracing said container and holding the container above said cap.
21. In combination, a fire extinguisher support comprising an inverted cap, a container breaking member movably mounted therein, a spring for actuating said member, heat controlled means for holding the member against actuation, a frangible container, and means embracing the container and holding the container above said cap and in the path of movement of the container breaking member.

In witness whereof, I have hereunto set my hand this 28th day of September, 1927.

WILHELM B. BRONANDER.
